PACKING DEVICE FOR PILE FABRICS

Sol Schwartz, 67-40 173rd St., Flushing, N.Y.

Filed July 1, 1957, Ser. No. 669,377

2 Claims. (Cl. 242-62)

This invention relates to cloth winding device and particularly concerns a rack or spool upon which long pile or nappy fabric is wound for shipment, together with means for securing the fabric on the rack.

Heretofore racks and spools for packing crushable fabrics have been provided with frames having arms on which are mounted radial series of spaced hooks adapted to engage the selvage edges of the fabric. The fabric is wound on the spool spirally with the several convolutions of the fabric out of contact with each other. The windings are so spaced that during shipment no injury can occur to the upstanding nap or pile due to rubbing of superimposed layers over one another.

In the present invention there is provided a rack having crossed arms with longitudinal channels provided with slots into which the fabric can be inserted. A flexible wire is arranged to be threaded through each channel to secure a selvage edge of the fabric therein. An automatic apparatus is provided for driving the binding wire through the fabric. The apparatus is so arranged that fabric of any practical length can be wound in generally spiral form on the rack and held securely with the successive layers out of contact with each other.

It is therefore a principal object of the invention to provide a novel rack or spool for packing pile fabric in a plurality of turns spaced from each other.

It is a further object to provide an apparatus for supporting a rack of the character described during the winding of a pile fabric thereon, the apparatus being provided with means for turning the rack and advancing a plurality of binding wires or rods therethrough.

It is a further object to provide a rack for packing pile fabric, the rack having two pairs of crossed arms spaced apart by a crossbar, each arm being a sheet metal structure having a turned edge forming a longitudinally extending channel, the wall of the turned edge having circumferential slots spaced uniformly along the channel.

It is a further object to provide an apparatus for automatically advancing a plurality of binding wires through the arms of a rack of the character described, said apparatus being provided with mechanical means for advancing the wires in each arm in turn.

It is another object to provide a packing apparatus for pile or napped fabrics, said apparatus including a novel winding spool or rack, means for supporting and turning the spool, and means for advancing binding wires through successive turns of the fabric.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a top oblique view of a rack according to the invention with a fabric wound thereon in a plurality of generally rectangular spiral turns.

2

Fig. 2 is a perspective view of one end of the rack.

Fig. 3 is a perspective view of a portion of one arm of the rack showing the turned and slotted edge.

Fig. 4 is a perspective view of a portion of an arm of the rack showing the selvage edge of a pile fabric impaled by a binding wire and held in a slot in the arm.

Fig. 5 is a sectional view taken on lines 5-5 of Fig. 4.

Fig. 6 is a front elevational view of a rack mounted in the turning and binding apparatus showing a fabric being wound thereon.

Fig. 7 is a sectional view taken on lines 7-7 of Fig. 6, with the fabric omitted.

Fig. 8 is an end view taken on lines 8-8 of Fig. 6 showing the apparatus with fabric omitted.

Fig. 9 is a top plan sectional view taken on lines 9-9 of Fig. 8.

Fig. 10 is a sectional view taken on lines 10-10 of Fig. 7 showing a portion of the wire advancing means.

Fig. 11 is a sectional view taken on lines 11-11 of Fig. 10.

Fig. 12 is a perspective view of a rack clamping means employed in the apparatus.

Fig. 13 is an exploded perspective view of portions of the rack clamping means.

Fig. 14 is a perspective view of a mounting plate for the rack.

The rack 20 shown in Fig. 1 is formed by two identical frames 22. Each frame is a sheet metal member bent in an hourglass or X-shape. Each frame has four arms 25. These arms are disposed in a cross or diagonal formation radiating from the flat bridge portion 26, as clearly shown in Figs. 1 and 2. The opposed ends 28 of the frame are flat plate-like portions. The frame is a rigid X-shape structure formed from the single sheet or strip of metal as above mentioned. Opposite ends of the strip meet in abutment at the bridge portion 26. A post or bar 30 joins corresponding flat bridge portions 26 of the two frames at opposite ends of the rack.

Bolts or rivets 32 serve to secure the frames 22 to bar 30 and also hold the ends of the strip forming each frame in abutment at the bridge portions 26. Bar 30 is somewhat narrower than the length of the bridge portion 26 so that clamping members of the winding and turning apparatus may be engaged thereon as is described below. A pile fabric P is wound on the rack in a plurality of generally rectangular spiral turns. Each turn of the fabric has four flat sides with each side spaced a predetermined distance from the adjoining sides. The spacing of the sides of the fabric is determined by the spacing of the slots 40 formed circumferentially in the rolled or turned edges of arms 25. The frames 22 are so disposed that for each radially extending arm 25 on one frame there is a corresponding coplanar radial arm on the other frame. Slots 40 extend a short distance into the arm, as best shown in Fig. 3. This arrangement permits the selvage end S of the pile fabric P to extend beyond the curved portion of the turned edge 42 as shown in Fig. 4. Thus the impaling wire 44 which passes through the longitudinal passage 45 in each turned edge 42 securely holds the fabric in the slot. Opposite ends of the wires 44 are twisted or tied together to form the ties 46 and 47 shown in Fig. 1. The binding wire 44 has a sharp pointed conical end 48. The pile P' of the fabric P terminates a short distance from the turned edge 42, so that the selvage S which is free of nap or pile is engaged in slots 40 of the turned edge. If desired, the flat wall extension 42' of the turned edge 42 may be secured by spot welds 54 or otherwise to the wall of arm 25. If desired, the arm 25 can be reinforced or stiffened by turning the edge 25' into a bent or rolled form as shown in Fig. 3.

70

In Figs. 6 to 14 are shown details of the apparatus employed for packing the pile fabric P on the rack 20. The winding and turning device has a frame formed by two pairs of upright bars 60 secured at opposite ends of a rectangular base plate 62. The upper ends of the bars 60 are joined by cross-bars 63 and 64 to form a rigid open rectangular frame structure. At each end of the frame is a circular ring 33 formed by four arcuate strips or plates 34 as shown in Fig. 8. The plates are supported by the horizontally disposed arms 35 and the vertical arms 36, 37. Arms 35 are joined to bars 60. Arm 37 is joined to crossbar 63 and arm 36 is joined to plate 62. The ring 33 fits into the circular groove 38 of a circular plate 39 which is best shown in Fig. 14. Plate 39 is thus rotatably mounted in ring 33. Supported on plate 39 and rotatable therewith is a rack clamping device 49. This device, as best shown in Figs. 12 and 13, includes a base plate 50 having a flange 51. The flange is provided with apertures 52 in which are engaged rivets or bolts 53 which pass through apertures 53' in plate 39 for securing the plate 50 to plate 39. Plate 50 has a pair of terminal fingers 55 which abut the end of bar 30 when the rack is held by the clamping device. A clamping plate 56 is provided to overlie the plate 50. This plate has a pair of apertures 57 through which extend the threaded bolts 58 anchored in plate 50. Wing nuts 59 are threaded on bolts 58. The rectangular plate 56 has a recess 61 into which fits the bridge portion 26 of the rack arms 25.

When the rack 20 is mounted in the clamping device 49 as shown in Figs. 6, 8 and 9, the rack is rotatable on a horizontal axis in the rings 33 at both ends of the frame. The fabric P may be manually inserted into the corresponding slots 40 of the respective arms 25 and the wires 44 may then be advanced through the passages 45 to pierce the selvaged ends S of the fabric P and thus secure the fabric in the rack. The wires 44 are advanced by the mechanism which will now be described.

In plate 39 are four slots 66 as best shown in Figs. 7 and 8. Through each of these slots passes an arm or lever 67. There are four such levers provided at each end of the frame. The levers are pivotally mounted in brackets 68 which are secured to the plate 39. The levers 67 serve as handles for advancing the wrench heads or elements 70 in outward radial directions with respect to each plate 39. The wrench heads 70 are best shown in Figs. 10 and 11. Each wrench head is a hollow, rectangular body formed on the end of lever 67 and disposed perpendicular thereto. Wire 44 passes through the opening 71 in wrench head 70. Within the opening are disposed two U-shaped leaf springs 72. The outer ends of the springs are secured to the wall of opening 71 and the free ends bear on the jaws 74. Each jaw 74 has inwardly extending teeth 75 which are directed so that the wire 44 can be advanced by the lever 67 when the lever is operated. Each jaw 75 pivots on a pintle 76 which extends through the upper and lower sides of the wrench head 70. In Fig. 11 the extent of advancement of wire 44 each time the lever 66 is operated is indicated by dotted lines. After each forward movement of the wire the wrench head moves backwardly or radially inward with respect to plate 39 without affecting the position of wire 44.

In Figs. 7 and 9 is shown the disposition of four wires designated 44^a, 44^b, 44^c, and 44^d. The wire is passed through to respective wrench heads 70 to enter the passages 45 in the turned edges 42 of each arm 25. The respective arms are designated 25^a, 25^b, 25^c and 25^d. It will be noted that wires 44^a and 44^b are disposed inwardly a short distance with respect to wires 44^c and 44^d. This is made possible by forming the arms 25^a and 25^b with greater width than the arms 25^c and 25^d, so that the

turned edges 42 of the arms 25^a and 25^b are disposed inwardly a short distance with respect to the turned edges 42 of arms 25^c and 25^d. Since wires 44^a, 44^c are respectively parallel to wires 44^b and 44^d, the wires do not interfere with each other. The wires are quite stiff so that they extend radially as shown in Figs. 7 and 8, but they are flexible enough to be twisted to form the ties 46, 47 shown in Fig. 1.

Each time the selvage edge of the fabric is inserted 10 in a slot 40 the appropriate lever 67 is manually operated to advance the pointed end 48 of wire 44 through the fabric. As each pair of coplanar arms on opposite sides of the rack is loaded with fabric, the rack is manually turned so that the next slots 40 in the following arms 25 15 may be engaged by the fabric being wound on the rack. After the rack is completely packed with the spirally wound fabric the clamping plates 56 are removed to release the rack. The ends of the wires extending out of the passages 25 at each end of each arm are tied together 20 as shown in Fig. 1.

The invention herein disclosed is related to that covered in copending patent application Serial No. 669,519 filed July 2, 1957 on Machine for Packing Pile Fabrics.

While I have illustrated and described the preferred 25 embodiment of my invention, it is to be understood that I do not limit myself to the precise construction herein disclosed and that various changes and modifications may be made within the scope of the invention as defined in the appended claims.

Having thus described my invention, what I claim as 30 new, and desire to secure by United States Letters Patent is:

1. A machine for winding and packing pile fabric comprising the combination of a base structure having horizontally spaced supports, a rack for spooling pile fabric removably journaled on a horizontal axis on said spaced supports, said rack having radiating arms carrying rows of longitudinally spaced pile fabric supporting fingers provided with binding wire guides located at the opposite sides of the spaces between said spaced fabric supporting fingers, pile fabric piercing wires slidably in said guides across said spaces and through layers of pile fabric disposed therein, clutch means in gripping engagement with said wires and means for shifting said clutch means in the direction to advance said binding wires through said guides and layers of pile fabric spooled on said spaced fingers said clutch means and said means for shifting the same being rotatable with said fabric spooling rack.

2. A machine for winding and packing pile fabric comprising the combination of a base structure having horizontally spaced supports, a rack for spooling pile fabric removably journaled on a horizontal axis on said spaced supports, said rack having radiating arms carrying rows of longitudinally spaced pile fabric supporting fingers provided with binding wire guides located at the opposite sides of the spaces between said spaced fabric supporting fingers, pile fabric piercing wires slidably in said guides across said spaces and through layers of pile fabric disposed therein, clutch means in gripping engagement with said wires and means for shifting said clutch means in the direction to advance said binding wires through said guides and layers of pile fabric spooled on said spaced fingers said rack being removably mounted in end plates rotatably mounted in said spaced supports of said base and said clutch shifting means being mounted in said rotatable end plates.
